CLAIM

The ornamental design for a lighter, as shown and described.

DESCRIPTION

FIG. 1 is a perspective view of a lighter showing my new design including the top, front and one side thereof;

FIG. 2 is a top plan view thereof;

FIG. 3 is a rear elevational view thereof;

FIG. 4 is a side elevational view showing the side opposite that shown in FIG. 1; and

FIG. 5 is a fragmentary rear perspective view of the upper portion thereof on an enlarged scale.
